UNITED STATES PATENT OFFICE.

OLIVER S. SLEEPER, OF BUFFALO, NEW YORK, ASSIGNOR TO BUFFALO FOUNDRY & MACHINE COMPANY, OF BUFFALO, NEW YORK, A CORPORATION OF NEW YORK.

IMPREGNATING APPARATUS.

1,154,447.

Specification of Letters Patent. Patented Sept. 21, 1915.

Application filed November 17, 1910. Serial No. 592,836.

To all whom it may concern:

Be it known that I, OLIVER S. SLEEPER, a citizen of the United States, residing at Buffalo, in the county of Erie and State of New York, have invented new and useful Improvements in Impregnating Apparatus, of which the following is a specification.

My invention relates to an impregnating apparatus which is more particularly designed for impregnating a tire fabric with a water proof liquid compound but the same may also be used for impregnating other fabric, paper or other sheet like material with other kinds of liquids, as for instance, paper used in electrical work and tape for covering electric wires.

In the accompanying drawings consisting of 4 sheets: Figure 1 is a vertical longitudinal section, partly broken away, of an impregnating apparatus embodying my invention. Fig. 2 is a vertical transverse section of the same taken in line 2—2, Fig. 1. Figs. 3, 4, and 5 are horizontal sections in lines 3—3, 4—4, and 5—5, Fig. 1, respectively.

My improved impregnating apparatus embodies a casing or housing which comprises a lower hollow base A and an upper hollow tower A¹ which rises from the central part of the top of the base. For convenience of manufacture this casing is made in sections, as shown in the drawings. Extending upwardly from the bottom of the base and into the tower but stopping short of the top of the latter are two upright partitions a, a¹ which are arranged transversely within the base and tower and fit at their opposite vertical edges against the longitudinal walls b, b¹ of the base and tower, thereby forming an inlet or front chamber B in the front part of the base, an outlet or rear chamber B¹ in the rear part of the base, an ascending or front well or shaft B² in the front part of the tower which connects at its lower end with the inlet chamber, a descending or rear well or shaft B³ in the rear part of the tower which connects with the outlet chamber B¹ and an intermediate well or tank B⁴ which is arranged between the inlet chamber and ascending well and the outlet chamber and descending well and which is closed at its lower end and sides

but communicates at its upper end with the upper ends of both the ascending and the descending wells.

The corresponding vertical side edges of the upright partitions a, a¹ are connected with each other and provided with laterally projecting vertical ribs a² which engage with vertical grooves a³ in the adjacent side wall of the tower and base, as shown in Figs. 3, 4 and 5. By this means the outer walls of the tower and the partitions are free to expand and contract freely in a vertical direction independently of each other when affected by the differential in the temperature to which these parts are exposed, thereby preventing straining of these parts or opening any of the joints in the same which would permit leakage.

In the inlet chamber and ascending well B, B² the moisture is removed from the fabric to be impregnated, in the tank B⁴, the fabric is impregnated with the desired compound and in the descending well and outlet chamber B³, B¹ the solvents are removed from the impregnated material after the same has permeated the fabric or material under treatment.

The chamber B receives the fabric, cloth or other material to be treated preparatory to drying and impregnating the same and the chamber B¹ receives the material after the same has been impregnated. The ascending and descending wells B², B³ may be heated by any suitable means but preferably by means of coils c, c¹ through which may be circulated steam, hot water, oil or air or any other suitable heating medium. In the side walls and top of the inlet and outlet chambers the same are provided with observation windows or glasses d for admitting light into these chambers and also permitting of observing the operation of the parts within these chambers. At suitable intervals on the front and rear walls of the wells the same are provided with manholes, each of which is fitted with a hinged cover e which is equipped with a transparent pane e¹ of glass or the like to permit of observing the interior of the apparatus.

The top of the tower is closed by a cover composed of two sections f which are removable and hinged to the adjacent part of the

2
tower and each provided with an observation glass j^1 .

On opposite sides of the tower and communicating with the ascending and descending wells are vapor outlet nipples g , g^1 which are connected with an exhausting device of any suitable character for producing a vacuum in the casing and through which the moisture and vapors from the cloth and 10 the solvent from the compound are removed.

When a vacuum is produced within the casing an impregnating compound will be drawn through a pipe h from a supply tank H located alongside of the main casing and 15 into the lower part of the impregnating tank which holds the charge of impregnating compound during the operation of treating a web of tire fabric or similar material. The height to which the impregnating compound 20 is drawn into the impregnating tank will be governed by the locality and the barometric pressure where the apparatus is installed. The apparatus is, however, so constructed as to provide for considerable 25 leeway or fluctuations in the height of the level of the impregnating liquid in the impregnating tank.

The supply tank is fitted with stirrers H^1 for mixing the compound, with a coil H^2 for 30 heating the compound and with a number of transparent panes of glass h^1 for noting the interior of the same and the height of the compound therein. The level of the liquid in the impregnating tank is regulated by 35 the supply tank, inasmuch as liquid added to the supply tank will increase the height of the liquid in the impregnating tank. Additional compound may be added to the supply tank so that the same is fed over into 40 the impregnating tank and compensates for the compound which is taken up by the cloth or fabric under treatment.

The fabric or cloth ω to be treated is 45 unwound from a roll mounted horizontally on a supply arbor I arranged transversely in the inlet or receiving chamber B and passes thence inwardly between a pair of horizontal feed rollers i , i^1 , thence upwardly through the front or ascending well 50 B^2 and adjacent to the heating coils therein, whereby the fabric is dried and the moisture is carried away under vacuo through the vapor outlets g , thence inwardly and downwardly over a front elevated supporting 55 roller J into one side of the impregnating tank containing the bath or charge of impregnating compound, thence underneath and upwardly around a lower supporting roller K arranged at the lower end of the impregnating 60 tank and through the charge of impregnating compound in the impregnating tank, thence outwardly and downwardly around a rear elevated supporting roller J^1 and 65 through the rear or descending well B^3 , and adjacent to the heating coils therein, thence

underneath and outwardly around a rear lower supporting roller k arranged in the outlet or rear chamber, and then is wound in the form of a roll around a receiving arbor L arranged horizontally and transversely in the last mentioned chamber. The roller i is preferably journaled in fixed bearings but the roller i^1 is movable bodily and held yieldingly against the roller i by means of a weighted lever i^2 . As the fabric 75 moves downwardly and upwardly in the form of a depending loop through the compound in the impregnating tank the fabric becomes impregnated with the compound 80 therein.

Projecting downwardly from the top of the tower and into the upper part of the impregnating well is a transverse baffle j which fits at its opposite vertical edges against the adjacent sides of the impregnating tank and divides the upper part of the same into a descending throat j^1 through which the fabric passes downwardly and an ascending throat j^2 through which the fabric passes 85 upwardly. The level of the liquid impregnating compound is preferably of such height when the machine is in operation that the lower end of the baffle j dips at its lower end into the impregnating liquid, thereby forming a liquid seal between the 90 throats and preventing the vapors from passing from one side to the other. The descending throat j^1 is preferably made comparatively narrow this being preferably effected by providing the adjacent sides 95 of the front partition a and the baffle j forming the walls of this throat with fillings j^3 of any suitable material which are arranged close to the opposite sides of the fabric. By this means the descending throat 100 through which the fabric passes upon entering the impregnating tank is reduced in area to prevent undue evaporation of the compound in the ascending well of the apparatus and also to prevent the liquid compound from creeping upwardly through the descending throat or passage which otherwise would be liable to occur owing to the action of capillary attraction which would 105 tend to carry the impregnating compound or liquid up through the cloth or fabric and to the upper supporting roller J on this side of the baffle. As the fabric leaves the upper end of the ascending throat j^2 the 110 fabric is scraped on both sides by means of scrapers m , m^1 , engaging with opposite sides thereof, thereby removing any surplus liquid from the fabric and returning the same to the impregnating tank. The scrapers 115 m , m^1 are mounted respectively on horizontal transverse shafts M , M^1 journaled in the walls of the tower and provided outside of the latter with weighted arms M^2 , M^3 which 120 operate to hold the scrapers m , m^1 yieldingly in engagement with the fabric.

125
130

The underside of the upper rear supporting roller J^1 is also engaged by a scraper m^2 which removes any impregnating compound adhering thereto and returns the same to the impregnating tank, this last mentioned tank being mounted on the adjacent part of the tower wall.

The compound in the impregnating tank is kept heated to the proper temperature by means of a heating coil k^1 arranged in the lower part of the impregnating tank below the lower supporting wheel or roller K whereby the heat from the coil k^1 together with the heat derived from the coils c, c^1 , adjacent to the partitions a, a^1 maintain the compound in the impregnating tank at the proper temperature. Each coil is provided with any suitable means whereby the heating effect of the same may be regulated.

20 In rolling up the finished fabric on the arbor L a separating web n consisting preferably of oil paper is fed from a roll n^1 in between the several coils or convolutions of the finished fabric as the same are wound 25 upon the arbor L , thereby preventing the layers of the fabric from adhering to each other.

The roll k is engaged by a scraper l^1 which operates to remove any compound 30 therefrom and keep the same clean, the compound thus removed being permitted to fall on the fabric or cloth and to be rolled up with the same, the surplus of material on some parts of the fabric not being objectionable.

Thermometers K^2 of any suitable construction may be placed in the casing at different locations for the purpose of determining the temperature of the compound and 40 vapors and for the same reason one or more thermometers k^2 are placed in the supply tank H .

The rollers i, J, K, J^1, k and the winding up arbor L are driven by power and preferably by gearing located on one side of the apparatus and of any suitable construction but preferably that shown in the drawings. This gearing, as shown, comprises a worm o and worm wheel o^1 which intermesh, a cone 50 pulley o^2 for driving the worm, a lower longitudinal shaft o^3 journaled on the lower part of the casing and carrying the worm wheel o^1 , bevel wheels o^4, o^5, o^6 , arranged on the shafts of the rollers i, K and k and meshing 55 with bevel wheels o^7, o^8, o^9 , on the longitudinal shaft, a friction pinion o^{10} mounted on the longitudinal shaft and engaging a friction wheel o^{11} on the outer end of the arbor L , an upper longitudinal shaft o^{12} 60 journaled on the tower and provided with bevel wheels o^{13}, o^{14} meshing with similar wheels o^{15}, o^{16} on the shafts of the upper supporting wheels J, J^1 , and an upright shaft o^{17} journaled on the casing and connected by an upper pair of intermeshing

bevel wheels o^{18} with the upper longitudinal shaft and provided with a lower bevel wheel o^{19} meshing with the bevel wheel o^5 .

The apparatus is so devised that the vacuum is the same in the machine on both sides 70 of the baffle j and cannot be destroyed in the space on one side of the same without similarly affecting the space on the other side of the same. This is preferably effected by connecting the inlet and outlet chambers and 75 associated spaces by a pipe K^1 having a single vent valve K^2 whereby the vacuum in these chambers and the spaces connecting therewith is equalized or balanced and the same may be simultaneously connected with 80 or disconnected from the atmosphere. The outer ends of the inlet and outlet chambers are provided with doors c^2, c^5 to permit of free access to the base for introducing an untreated roll of fabric and removing a 85 treated or impregnated roll of fabric therefrom. Each of the supporting rollers J, J^1, K is capable of being removed axially out of the casing through an opening in the latter each of these openings being normally closed 90 by a cover c^3 . Wherever necessary, manholes are also placed in the casing to permit of stringing a pilot strip through the machine whereby the fabric to be treated is threaded through the machine, manholes of 95 this character being shown for instance on the outer sides of the inlet and delivery chambers which are normally closed by doors c^2, c^5 and also on the front and rear sides of the impregnating tank at the lower 100 end thereof at which latter place the manholes are closed by covers c^4 .

In operating this machine the same is used in connection with two surface condensers Q, Q^1 under vacuum, one dry vacuum pump 105 R , an expansion pan or chamber S and an atmospheric condenser T which are connected as shown in the drawings and each of which may be of any suitable and well known construction. The purpose of the 110 two surface condensers is to permit of attaching one Q , to the vapor outlets q on the front side or ascending well of the tower for withdrawing the moisture from the cloth and reclaiming the moisture while the other 115 Q^1 , is connected with the vapor outlets q^1 on the rear side or descending well of the tower for removing the solvents from the compound which may be carried over by the impregnated fabric and thus permit of reclaiming these solvents. These two surface condensers are attached to the same inlet of the vacuum pump above mentioned. Should any solvent enter the condenser Q when reclaiming the moisture from the fabric the 120 same would be again evaporated owing to this condenser being under vacuum and this solvent being more volatile than water. The other condenser Q^1 operates to reclaim some 125 of the solvent but part of it will be again 130

evaporated and enter the air cylinder of the vacuum pump. This air cylinder discharges this solvent vapor into the expansion pan S which latter serves the purpose of equalizing 5 the exhaust of the pump and preventing pulsations thereof. The expansion pan is attached to the atmospheric condenser which operates as an atmospheric seal to prevent the escape of vapors and cause them 10 to condense and fall back into the expansion pan. The latter and the condensers are water jacketed and are cooled with water in the usual manner to cause the condensation of the vapors passing through the same. The 15 solvents so recovered may be put back into the compound, if desired, in such amounts as may be necessary to keep the compound of the proper consistency, the solvent being preferably added to the compound in the 20 auxiliary tank H. The fabric to be impregnated is introduced into the inlet chamber through the opening in the casing which is normally closed by the door c^2 and the finished fabric is removed from the outlet 25 chamber through the opening thereof which is normally closed by the door c^5 .

In order to maintain the fabric at the proper temperature while the same is being wound on the arbor L the outlet chamber is 30 heated preferably by a steam coil k^2 , as shown in Fig. 1. By —— means of the friction gearing for driving the receiving arbor L the variation in the speed of the roll 35 of finished fabric at the periphery thereof due to the constant increase of its diameter as the fabric winds up is compensated for and the fabric is kept under constant tension.

In the bottoms of the inlet and outlet 40 chambers are arranged drain pipes p containing valves p^1 which permit of removing from these chambers any liquid or solvents which may gather therein.

Owing to the impregnating liquid being 45 supported in the form of an upright column the fabric, before entering this liquid at the top of the impregnating tank, may be thoroughly evacuated and as this evacuated fabric descends in the compound it gradually comes under increasing pressure upon approaching the bottom of the impregnating 50 tank, whereby the compound is forced into the evacuated fabric and the latter becomes thoroughly impregnated.

It will be noted that in the construction of 55 this apparatus as shown in the drawings all operations of the apparatus may be controlled from the floor on which the same rests.

I claim as my invention:

60 1. An impregnating device comprising a vacuum chamber, a tank for holding an impregnating fluid arranged within said vacuum tank, means for supplying an article to be impregnated to said tank and arranged 65 within said chamber and outside of said

tank, means for receiving the impregnated article from said tank and arranged within said chamber and outside of said tank and guiding means which are arranged within the tank and around which said article is 70 adapted to pass while moving from the supplying and receiving means outside of the tank.

2. An impregnating apparatus comprising 75 a vacuum casing adapted to be connected with an exhausting device, a tank for holding an impregnating liquid arranged in said casing, and a baffle arranged within said casing and projecting from said casing into said tank and forming inlet and outlet 80 throats for the passage of the article to be treated.

3. An impregnating apparatus comprising 85 a casing having an inlet chamber, an outlet chamber, upright wells connected at their lower ends with said chambers, respectively, a tank adapted to hold an impregnating liquid communicating at its upper end with said wells, and means for moving a sheet like material from said inlet chamber 90 upwardly through one of said wells, thence downwardly and upwardly through said tank, and thence downwardly through the other well into said outlet chamber.

4. An impregnating apparatus comprising 95 a casing having an inlet chamber, an outlet chamber, upright wells connected at their lower ends with said chambers, respectively, a tank adapted to hold an impregnating liquid communicating at its upper end 100 with said wells, means for heating the interior of said casing, and means for moving a sheet like material from said inlet chamber upwardly through one of said wells, thence downwardly and upwardly through said tank, and thence downwardly through the other well into said outlet chamber.

5. An impregnating apparatus comprising 110 a casing having an inlet chamber, an outlet chamber, upright wells connected at their lower ends with said chambers, respectively, a tank adapted to hold an impregnating liquid communicating at its upper end with said wells, and means for moving a sheet like material from said inlet chamber 115 upwardly through one of said wells, thence downwardly and upwardly through said tank, and thence downwardly through the other well into said outlet chamber comprising supporting rollers arranged in the casing at the lower ends of said wells and tank and at the upper ends of said wells.

6. An impregnating apparatus comprising 120 a casing having an inlet chamber, an outlet chamber, upright wells connected at their lower ends with said chamber, respectively, a tank adapted to hold an impregnating liquid communicating at its upper end with said wells, and means for moving 125 a sheet like material from said inlet chamber 130

ber upwardly through one of said wells, thence downwardly and upwardly through said tank, and thence downwardly through the other well into said outlet chamber comprising supporting rollers arranged in the casing at the lower ends of said wells and tank and at the upper ends of said wells, a supply arbor which is arranged in said inlet chamber and from which the material 10 is unwound, and a receiving arbor which is arranged in the outlet chamber and upon which the material is wound.

7. An impregnating apparatus comprising a vacuum casing, a tank for holding an 15 impregnating liquid arranged in said casing, and means for slidingly connecting the casing and tank comprising a rib arranged on one of said members and engaging with a groove in the other member and dividing the 20 space within the casing into two wells which communicate at their upper ends with the upper end of the tank.

8. An impregnating apparatus comprising a casing, a tank arranged wholly within 25 said casing and adapted to hold an impregnating liquid, a well communicating at its upper end with the upper end of said tank, and means for moving a sheet like article

upwardly through said well and downwardly and upwardly through said tank. 30

9. An impregnating apparatus comprising a casing, a tank arranged wholly within 35 said casing and adapted to hold an impregnating liquid, a well communicating at its upper end with the upper end of said tank and means for moving a sheet like material downwardly and upwardly through said tank and downwardly through said well.

10. An impregnating apparatus comprising 40 a casing, a tank arranged wholly within said casing and adapted to hold an impregnating liquid, two wells connected at their upper ends with the upper end of said tank, and means for moving a sheet like article 45 upward through one well, thence downwardly and upwardly through said tank, and thence downwardly through the other well.

Witness my hand this 9th day of November, 50 1910.
